(57) **CLAIM**

The ornamental design for a slider for a slide fastener, as shown and described.

DESCRIPTION

FIG. 1 is a front elevational view of a slider for a slide fastener of the claimed design;

FIG. 2 is a back elevational view of the design of FIG. 1;

FIG. 3 is a top view of the design of FIG. 1;

FIG. 4 is a bottom view of the design of FIG. 1;

FIG. 5 is a left-side view of the design of FIG. 1;

FIG. 6 is a right-side view of the design of FIG. 1;

FIG. 7 is a cross-sectional view of the design of FIG. 1, taken on section lines 7—7 of FIG. 1; and,

FIG. 8 is a cross-sectional view of the design of FIG. 1, taken on section lines 8—8 of FIG. 1.
